WIRE DRAWING MACHINE

Lorenzo A. Laribee, Cemetery Road, Camden, N.Y.
Filed Aug. 6, 1959, Ser. No. 832,059
4 Claims. (Cl. 205—13)

This invention relates to a wire drawing machine and more particularly to a high speed, compact machine of greatly improved efficiency.

In the wire drawing industry, in order to obtain practical rates of production of wire drawing, it is very necessary and important to control the temperature of the wire to prevent undesired variations of characteristics therein due to overheating. For small size wires this is particularly important and continuous cooling is almost a necessity. The practice of immersing the drawing dies and heads completely in a cooling solution which is continuously circulated to the drawing station has thus grown up. Since in a single pass through a machine a number of dies may be used to produce the desired reduction in size, the stringing up operation can become quite involved and time consuming to ensure that the wire is wrapped around the drawing heads in the proper manner and is inserted through the desired dies and so forth. In the usual machine, this necessitates either the removal of the cooling fluid which, if drawing has been going on, is normally quite hot or working directly in the hot fluid which is extremely uncomfortable for the operator to say the least.

To overcome this problem, various devices have been proposed in which the entire drawing head may be pivoted out of the cooling tank to provide access to the drawing heads outside of the cooling medium. Generally these machines have been rather large involved machines requiring special installations and highly expensive and complicated driving arrangements requiring very large power equipment to drive the necessary gear trains and auxiliary driving system to perform the drawing operation. According to my invention I have provided a very simple, compact machine that requires a minimum of driving power to produce maximum reduction in gauge of wire all in a very high speed operation. Briefly I accomplish this by providing a driving motor directly above the cooling tank and fixing the drawing head directly on the motor shaft without any intermediate gear trains.

Accordingly, it is an object of the present invention to provide an improved wire drawing machine of greatly increased efficiency for accomplishing a maximum reduction in size of wire per minimum amount of floor space. It is another object of the present invention to provide an improved wire drawing machine in which the drawing wire is continually immersed in cooling and lubricating solution and in which the drawing heads may be readily removed from the solution for adjustment or stringing up thereof without draining of the coolant. It is another object of the present invention to provide a wire drawing machine in which a large number of reductions may be made in an extremely small space. It is a still further object of the present invention to provide a wire drawing machine for large reductions in wire size with a minimum amount of driving power. It is still further object of the present invention to provide a wire drawing machine utilizing a plurality of driving motors each relatively small in size and each being utilized at its maximum efficiency for its particular operation. It is a still further object of the present invention to provide a wire drawing machine for making a large number of reductions in wire size in a minimum of space and for winding the finished wire on a reel ready for further operations all in a self-contained compactly arranged unit. These and other and further objects will be in part apparent and in part pointed out as the specification proceeds.

2

In the drawings:

FIGURE 1 is a front elevation of the machine according to the present invention;

FIGURE 2 is a left side elevation of the machine of FIGURE 1;

FIGURE 3 is a right hand side elevation of the machine of FIGURE 1 with the drawing heads withdrawn from the cooling tank;

FIGURE 4 is a sectional view, partially broken away, taken on line IV—IV of FIGURE 3 showing the drawing heads and die arrangement;

FIGURE 5 is a fragmentary elevational view of a portion of the die holder with dies therein;

FIGURE 6 is a fragmentary plan view of the die holder; and

FIGURE 7 is a partial elevational view of the reel drive mechanism.

Referring now to the drawings, the machine 10 according to the present invention comprises generally a frame portion 12 having four legs 14 carrying on the upper ends thereof a tank 16. A totally enclosed motor 18 is pivotally carried on pivot arms 20 mounted on each side of the tank 16. The bottom portion of the frame 12 carries between the legs 14 a take-up reel 22 driven by auxiliary motor 26 mounted on an angle bracket 28 on the back of the frame 12. Motor 26 also drives a level wind mechanism 30 for ensuring level winding of the wire on the take-up reel 22 as it comes out of the drawing apparatus above. Take-up reel 22 is quickly and easily mounted in frame 12 by cam and spindle assembly 24.

The actual drawing apparatus comprises the motor 18 which is mounted on a pair of plates 32 and 34 (see FIGURE 3) which in turn are mounted by arms 36 to the pivot arms 20 mounted on the tank 16. Motor 18 is on the order of seven and one-half horsepower and has the shaft extending outwardly from both ends of the housing. The housing of motor 18 is fixed to the plate 32 so that the shaft 38 extends therethrough and carries on the end extending below plate 32 driving head 40 which is a seven step inverted cone type of pulley which will be described in more detail herein. The casing of motor 18 is also secured to the plate 34 on the side thereof to make a firm and rigid mounting. Also mounted on plate 34 on the other side thereof is a second or auxiliary shaft 42 which extends through the plate 32 in a fashion similar to the main shaft 38 and carries on the end thereof a second driving head 44 similar to head 40. Shaft 42 is journaled in bushings or pillow blocks 46 mounted on plate 34. Shaft 42 is driven by a timing belt 48 from the main shaft 38 which projects beyond the top of the casing of motor 18. Suitable pulleys, are provided on shaft 38 and on shaft 42 to provide the desired speed ratios of the two drawing heads 40 and 44. The speed of the two shafts is normally equal. Shaft 38 also carries on the end thereof outwardly or upwardly from the driving belt 48 a capstan 50 which is secured in the usual manner to the shaft 38.

Mounted on the plate 32 in between the drawing heads 40 and 44 is a die assembly 52 which, as may be seen in better detail in FIGURES 5 and 6, is of a generally diverging V-shape having therein a plurality of slots adapted to receive therein the actual drawing die of the desired size. The dies 54 are of conventional construction having therein usually some form of a diamond drawing orifice mounted in a carrier of steel or other metal so as to fit within the slots of the frame 52 in a loose fashion.

In normal operation the machine is in the configuration of FIGURES 1 and 2 and the wire 56 to be drawn is brought down on the left side of the machine over pulley 58 and into the drawing heads 40 and 44 as will be described in detail herein. After the desired reduc-

tion the wire is drawn up through the plate 32 over pulley 60 mounted on arm 62 wrapped around capstan 50 twice and then back over pulley 64 mounted on arm 66 and thence down to the pulley 68 on the level wind mechanism 30 and thence to the actual take-up reel 22. The wire 56 after it passes over pulley 58 under the plate 32 enters through a die 76 (FIG. 4) mounted on the bottom of plate 32 and then around the lowest step 72 of the drawing head 40. The wire then proceeds through one of the dies 54a mounted in the die rack 52 to the lowest step 74 of drawing head 44 for one turn then back through a die 54b on the other side of the die rack 52 around the lowest or first step of the drawing head 40 again, through a die 54c on the other side of rack 52 around the second step of head 44 and then to successive steps of heads 40 and 44 until it is wrapped around and comes off the seventh step of drawing head 40 whence it is brought up over pulley 75 (FIG. 4) mounted on the bottom of plate 32 and up through a die carrier and die 78 positioned in plate 32 and thence to the pulley 60, as previously described. With both the drawing heads 40 and 44 being powered, illustratively a reduction from a wire entering size of No. 14 B & S gauge to a No. 30 B & S gauge is accomplished in a single pass through the machine 10. This is done as can be seen through a series of sixteen dies all immersed in a cooling fluid 80 in the tank 16 so that the maximum desired drawing is obtained without adversely affecting the characteristics of the drawn wire.

It should be understood that for a full reduction from 14 to 30 the wire as it passes over the heads 40 and 44 slips relative thereto to compensate for the elongation obtained. The diameter of the pulley steps is adjusted to partially compensate for and reduce the slippage. For a reduction from 14 to 22 namely passing the wire through eight dies only, the machine is non-slip with the pulley steps compensating completely for the elongation. For sizes intermediate 22 to 30 there is some slipping but if the omitted dies are taken from the top of the die holder (FIGURE 4) practically no slip is encountered. With this machine it is possible to have operating speeds of three thousand feet per minute and the overall dimensions of the machine are generally on the order of thirty inches long by twenty inches wide by about sixty inches high.

The tank 16 is filled with cooling fluid 80 to within one-half inch of the top. Cooling fluid 80 is normally circulated through tank 16 from an input pipe 82 to an output pipe 84 in any desired conventional manner. Overflow nipple 81 may be adjusted in output pipe 84 to give the precise fluid level desired. Removal thereof will permit tank 16 to be drained. The cooling fluid 80 consists normally of water and a lubricant as is standard in the industry. With the machine in the position shown in FIGURES 1 and 2 a very close fit is maintained about the plate 32 which acts as a top for the tank 16 so that no fluid splashes out onto other parts of the machine or the operator. Also with this arrangement, little if any dust can escape from the drawing operation to contaminate the surrounding atmosphere.

Take-up reel 22 is mounted on a spindle assembly 24 which consists of a fixed spindle 86 having a tapered end which engages in a hole in the left hand plate (see FIGURE 1) of the take-up reel 22 and a movable spindle 88 which is slidably mounted in sleeve 90 on the right hand side of FIGURE 1 and adapted to engage a hole in the right hand plate of the take-up reel 22. Sleeve 90 has therein a cam slot 92. A lever 94 is fixed in spindle 88 and upon rotation in the cam slot 92 causes the spindle 88 to move inwardly and outwardly of the sleeve 90 so as to engage and disengage the take-up reel 22. In this manner, any size take-up reel 22 can be readily positioned within the frame 12 and removed when it has been filled in one quick and easy operation. A suitable spring or weight 91 is attached to the end of lever 94 to maintain it in reel engaging position.

Take-up reel 22 is driven by the auxiliary motor 26 through a friction drive arrangement 96 which will be described in detail herein so as to constantly maintain a takeup tension on the wire as it comes from the capstan 50 over the level wind mechanism 30 thereto. The level wind mechanism 30 is also driven by the motor 26 through a belt or chain 98 from the take-up reel shaft as may be seen in FIGURE 2.

Friction drive arrangement 96 consists of a shaft 99 mounted on frame 12 in any convenient manner. Shaft 99 has fixed on it three or more pulleys 100 and has a yoke 102 rotatably mounted thereabout. Yoke 102 carries at the bottom a shaft 104 which has rotatably fixed thereon a corresponding three or more pulleys 106. Three or more belts 108 are positioned about pulleys 100 and 106 to form a broad friction surface for engagement with the wire on take-up reel 22. Shaft 99 is driven from motor 26 by belt 110 and pulley 111 fixed thereto and the belts 108 are held in contact with reel 22 by weight 112. Weight 112 is connected by cable 114 to yoke 102 over pulley 116. In this manner reel 22 is always maintained in a position to keep a tension on the finished wire as it comes off the capstan 50.

Obviously instead of multiple pulleys 100 and 106 and belts 108 a single wide grooved pulley and belt assembly could be used.

In use, the machine is first placed in the position of FIGURE 3 and the wire to be drawn fed through the mechanism as described above until it is completely hooked up about the drawing heads 40 and 44 and the dies 54 and thence brought up and about the capstan 50. The entire motor is then tipped down into the tank 16 to the position shown in FIGURES 1 and 2 and the wire brought from the capstan down to the level wind mechanism and on to take-up reel 22. The machine is then started and it will run completely automatically without further attention until the take-up reel 22 is full. At this point the friction drive arrangement 96 will trip a suitable stop mechanism not shown which will stop the machine, if desired, the operator can stop the machine by simply throwing the main switch which controls the power to the main motor and auxiliary motor of the machine 10. If a break in the wire should occur, the machine may be simply and easily tilted to the position of FIGURE 3, the wire restrung and then placed in its operating position all without the operator having to place his hands in the hot cooling and lubricating fluid 80 in the tank 16. Also in this configuration the heads 40 and 44 and dies 54 are much more readily accessible for cleaning and replacement.

While there is given above a certain specific example of this invention and its application in practical use, it should be understood that it is not intended to be exhaustive or to be limiting of the invention. On the contrary, this illustration and explanation herein is given in order to acquaint others skilled in the art with this invention and the principles thereof and a suitable manner of its application in practical use, so that others skilled in the art may be enabled to modify the invention and to adapt and apply it in numerous forms each as may be best suited to the requirement of a particular use.

I claim:

1. A wire drawing machine comprising in combination a main frame portion having a plurality of legs for supporting said machine on a floor surface, a cooling and lubricating fluid tank mounted adjacent the top of said frame portion a single electrical motor having a normally vertically disposed shaft pivotally mounted above said tank adapted to be pivoted from an operating vertical to a non-operating horizontal position relative thereto, an auxiliary shaft mounted parallel to said motor shaft and spaced therefrom on said motor so as to pivot therewith, belt and pulley means mounted on one end of said shafts for driving said auxiliary shaft from one end of said motor shaft, wire drawing head members mounted

on the other ends of the motor shaft and said auxiliary shaft, a die frame member mounted between said drawing heads, a plurality of dies carried within said die frame member, a capstan mounted on the end of said motor shaft opposite said drawing head, take-up reel means mounted within said frame portion below said tank means, auxiliary motor means mounted on said frame for driving said take-up reel, friction drive means operatively connecting said auxiliary motor and said take-up reel, a first guide pulley mounted on said motor adjacent said heads for guiding the wire to be drawn from an external supply to said drawing heads, a second guide pulley mounted on said motor for guiding said wire from said drawing heads to the other end of said motor, a third guide pulley mounted on said motor for guiding said wire to the capstan, a fourth guide pulley on said motor for guiding said wire from said capstan downwards, and a fifth guide pulley mounted on said frame for guiding said wire to said reel, whereby an extremely compact, high speed drawing machine is obtained in minimum of cubic and floor space.

2. A wire drawing machine comprising in combination a main frame portion adapted to support the machine on a floor surface, a coolant and lubricating fluid tank mounted in said frame portion adjacent the top thereof, a take-up reel assembly mounted in said frame below said tank portion, a top cover plate member for said tank, a main drawing motor mounted on said plate member and having a shaft extending through said plate member, an auxiliary shaft member mounted on said motor and extending through said plate member, a pair of pivotally connected arms fixed respectively to said plate member and said tank at each side thereof whereby said plate, motor and auxiliary shaft are pivotally mounted for movement from a horizontal to a vertical position relative to said tank and vice versa, seven-step drawing heads mounted on the motor shaft and auxiliary shaft below said plate member, die holder means mounted on said plate between said drawing heads, pulley means mounted on the other end of said motor and auxiliary shafts, belt means interconnecting said pulley means for driving said auxiliary shaft in synchronism with said motor shafts, a capstan member mounted on the upper end of said motor shaft, pulley means mounted on one edge of said plate for guiding the input wire to be drawn by said drawing heads, die means mounted in said plate for guiding the exit of the drawn wire therefrom to said capstan and take-up reel, auxiliary driving means for rotating said take-up reel, and movable spindle mounting means for said take-up reel to readily permit mounting of said take-up reel in said wire drawing machine.

3. A wire drawing machine comprising in combination a main frame portion adapted to support the machine on a floor surface, a fluid tank mounted in said frame portion, a coolant and lubricating fluid in said tank, a take-up reel assembly mounted in said frame portion below the fluid tank, a top cover plate member for said tank, a main drawing motor having a main shaft and an outer casing mounted on said top cover plate member, an auxiliary shaft member mounted adjacent to said main drawing motor in a position generally parallel to the shaft of

said motor, hinge means joining said top cover plate to said tank portion for pivotal movement of said cover and motor relative to said tank, one end of the motor shaft and auxiliary shaft extending through said top cover plate and the other end extending beyond the motor casing, timing belt and pulley means mounted on one end of said shafts for synchronizing rotation thereof, multi-step drawing heads mounted on the other end of the motor shaft and auxiliary shaft below said plate member, die holder means mounted on said plate between said drawing heads, a plurality of die members positioned in the said die holder means, input and output pipe means adapted to control the level of the cooling and lubricating fluid in said tank.

15 4. A wire drawing machine comprising in combination a main frame portion adapted to support the machine on a floor surface, a cooling and lubricating fluid tank mounted in said frame portion above the mid-section thereof, a takeup and level wind reel assembly mounted in said frame below said tank, auxiliary motor means mounted on said frame and operatively connected to said takeup reel assembly, a main drawing motor having the shaft thereof extending outwardly of both ends of housing thereof, an auxiliary shaft member of approximately equal length to the main motor shaft mounted on said motor housing in a manner generally parallel to the main motor shaft, mounting means for said main drawing motor fixed to said frame portion, said mounting means including hinge members adapted to pivot said main drawing motor from a vertical operative to a horizontal inoperative position, one end of the motor and auxiliary shafts extending into said tank when in the operative position, multi-step drawing heads mounted on the ends of said shafts adapted to extend into said tank, die and die holder means mounted between said drawing heads on said motor for pivotal movement therewith, a capstan member mounted on the other end of said motor shaft, a first guide pulley mounted on said motor adjacent said heads for guiding the wire to be drawn from an external supply to said drawing heads, a second guide pulley mounted on said motor for guiding said wire from said drawing heads to the other end of said motor, a third guide pulley mounted on said motor for guiding said wire to the capstan, a fourth guide pulley on said motor for guiding said wire from said capstan downwards, and a fifth guide pulley mounted on said frame for guiding said wire to said reel, whereby a large number of wire reductions may be accomplished in a minimum of cubic feet of space.
